(57) **CLAIM**

The ornamental design for the barrel rail planter, as shown and described.

DESCRIPTION

This application is related to Design Patent application Ser. Nos. 29/571,928 and 29/571,930, both filed concurrently herewith.

FIG. 1 is a perspective view showing a barrel rail planter in accordance with a new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines represent portions of the planter and form no part of the claimed design.
